UNITED STATES PATENT OFFICE.

JOSEPH SCHOENFELD, OF ALAMEDA, CALIFORNIA.

GAS HEATER.

Application filed September 22, 1926. Serial No. 136,948.

This invention relates to gas heaters such as are adapted to be placed in a room or like place to be heated and especially to a heater which will serve both as a radiation and air 5 circulating heater.

The object of the present invention is to generally improve and simplify the construction and operation of gas heaters to increase their general efficiency and utility; to so construct a heater that all gases and products of combustion may be thoroughly vented; to provide a glow section consisting of a thin section of metal or the like which may be heated to a glowing temperature by the 10 burner; to provide a reflector adapted to cooperate therewith, whereby both the heat and light rays radiating therefrom may be projected into the room and further to provide means whereby air may be freely circulated 15 through the heater and heated and directed 20 into the room.

One form which the invention may assume is shown by way of illustration in the accompanying drawings, in which:

25 Figure 1 is a front view of the heater,
Figure 2 is a cross section taken on the line II—II of Figure 1,
Figure 3 is a longitudinal section.
Referring to the drawings, in detail, it will 30 be noted that the heater consists of a housing generally indicated at A. This housing consists of a back section 2, a top or grill section 3, a front section 4 and an intermediate section 5, which is interposed between the grill 35 and the front section, the section 5 being a reflector as will hereinafter be described.

Cooperating with the front section 4 and disposed intermediate said section and the back section 2 is an intermediate back section 40 6. This back section divides the housing into two chambers generally indicated at 7 and 8. The chamber 7 will hereinafter be referred to as the combustion chamber and the chamber 8 as the air circulating chamber. 45 Mounted interior of the combustion chamber and extending substantially from end to end thereof, as shown in Figure 3, is a gas burner 9 of suitable construction, gas being supplied to the burner from an exterior source 50 such as a pipe 10 and the flow of gas being regulated by means of a valve 11.

The burner is also provided with a mixing chamber generally indicated at 12. As in usual practice, air and gas mixes in the chamber 55 and enters a lower section 13. This section is connected with the upper or burner

section 9, as at 14 and the mixture of gas and air discharges from the tips of the burner indicated at 15. The flame of the burner strikes a glow plate generally indicated at 16 which 60 will hereinafter be described and the products of combustion escape through a duct or flue 17 which forms a part of the back plate 6. The housing, as a whole, is supported by front and rear legs, as indicated at 18 and 19, respectively, and the exterior finish is such as to 65 produce the best ornamental effects.

The several sections of the burner so far described are supported between the ornamental end plates 20 of which the front and 70 rear legs 18 and 19 form a part. The several sections 2, 3, 4, 5, etc., are secured between the end plates by supporting flanges 21 or the like and screws 22. Formed in the upper face of the front section 4 is a rectangular shaped 75 elongated opening 16^a. This opening extends substantially from end to end of the section 4 and it is covered or closed by means of the glow plate 16, previously referred to. This plate consists of a thin sheet of nichrome 80 metal, Monel metal or a like metal or material which resists oxidation under high temperatures, for instance, nichrome can safely reach a temperature of approximately 1800° F., before oxidation becomes noticeable. 85 Monel may similarly stand high temperatures and so may other materials. If nichrome is employed, it may be as thin as five or six thousandths of an inch.

A thin sheet of metal subjected to the direct 90 flame of the burner assumes a glowing temperature and as such radiates both light and heat rays. It will be noted that the plate 16 is slightly inclined and so is the reflector 5. By proper shaping of the reflector and the 95 correct inclination, practically all the heat and light rays radiated will be projected in a forward direction and all the radiated energy is thus directed forwardly into the room, and at the same time, a pleasing effect is obtained as the entire reflector appears to be in a glowing condition.

Air to support combustion within the chamber 7 is admitted through an elongated slot 23 formed in the bottom portion of the front 105 plate 4. The air entering through this slot also supplies the mixing chamber 12, as it enters the mixing chamber through the openings indicated at 24 (see Figure 2). The products of combustion as specifically stated 110 escape through the tube or vent 17 and as this may be connected with a suitable flue all gases

and products of combustion will be carried away and danger of polluting the atmosphere of the room or dwelling is entirely eliminated. The air circulating and heating chamber 8 is supplied with air through an elongated slot 25 extending from end to end of the bottom section. This air rises upwardly through an air passage 26 and enters the chamber 8 from where it discharges through a series of openings 3^a in the grill 3. The heated air thus enters the room and is not polluted with any of the products of combustion.

In actual practice, it should be realized that the walls of the combustion chamber and particularly the rear section 6 and the portion indicated at 6^a become exceedingly hot and that it is this heat which is depended upon to heat the circulating air. To promote conduction of heat from these surfaces to the air passing through the passages 8 and 26, fins or flanges are cast both on the inner and rear surfaces of the plate 6. The inner fins or flanges are indicated at 28 and the rear flanges at 29.

The inner flanges conduct the heat to the plate 6 and the heat is there conducted to the fins or flanges 29 which are in direct contact with the circulating air. In this manner practically all the B. t. u.'s. of the fuel is absorbed and conducted to the air and high efficiency is obtained, the efficiency being further increased by the projection of the heat and light radiating from the glow plate 16.

By referring to Figure 2, it will be noted that insulating material such as indicated at 35 is interposed between the edges of the plate 16 and the casting supporting the same. This is important as it materially reduces heat conduction losses and to that extent increases the radiating efficiency of the plate.

While certain features of the present invention are more or less specifically described, I wish it understood that various changes may be resorted to within the scope of the appended claims. Similarly that various materials and finishes of the several parts employed may be such as the manufacturer may decide or varying conditions or uses may demand.

Having thus described my invention, what I claim and desire to secure by Letters Patent is:—

1. In a heater of the character described, a housing having an opening formed therein, a gas burner within the housing and below said opening, a plate of thin imperforated material covering said opening and adapted to be heated to a glowing temperature by the flame of the burner to radiate heat and light rays, said plate preventing the escape of products

of combustion, and a discharge flue in communication with the housing to carry away the products of combustion.

2. In a heater of the character described, a housing having an opening formed therein, a gas burner within the housing and below said opening, an imperforated plate of thin material covering said opening and adapted to be heated to a glowing temperature by the flame of the burner to radiate heat and light rays, and a reflector disposed exterior of the casing and cooperating with the plate to project heat and light rays radiating therefrom.

3. In a heater of the character described, a housing having an opening formed therein, a gas burner within the housing and below said opening, an imperforated plate of thin material covering said opening and adapted to be heated to a glowing temperature by the flame of the burner to radiate heat and light rays, a reflector disposed exterior of the casing and cooperating with the plate to project heat and light rays radiating therefrom, and a discharge flue in communication with the housing to carry away the products of combustion.

4. In a heater of the character described, a housing having an opening formed therein, a gas burner within the housing and below said opening, a plate of thin material covering said opening and adapted to be heated to a glowing temperature by the flame of the burner, a reflector disposed exterior of the casing and cooperating with the plate to project heat and light rays radiating therefrom, a discharge flue in communication with the housing to carry away the products of combustion, and a second housing partially enclosing the first-named housing, said housing having openings formed in the top and bottom thereof to permit an upward circulation of air.

5. In a heater of the character described, a housing having an opening formed therein, a gas burner within the housing and below said opening, a plate of thin material covering said opening and adapted to be heated to a glowing temperature by the flame of the burner, a reflector disposed exterior of the casing and cooperating with the plate to project heat and light rays radiating therefrom, a discharge flue in communication with the housing to carry away the products of combustion, a second housing partially enclosing the first-named housing, said housing having openings formed in the top and bottom thereof to permit an upward circulation of air, and a plurality of flanges formed on the inner and exterior surfaces of the first-named housing to conduct the heat to the circulating air.

JOSEPH SCHOENFELD.
